UNITED STATES PATENT OFFICE

2,454,689

KNOT TYING MECHANISM

Robert L. Dashew, deceased, late of Baltimore,
Md., by Ruth L. Dashew, administratrix, Pittsburgh, Pa.

Application January 25, 1945, Serial No. 574,529

3 Claims. (Cl. 289—2)

1

This invention relates to knotters or knot tying mechanisms.

One object of the invention is to provide a knotter mechanism which will tie substantially a bow knot.

Another object of the invention is to provide a knotter mechanism which will tie a knot in one or more lengths of a cord, thread or strand.

A further object of the invention is to provide a knotter mechanism wherein one or more lengths of the thread or filament to be knotted is engaged by a pair of pivotally associated jaws to first form a loop in the filament after which the jaws engage and grip the filament at another point and the filament so manipulated as to pull the gripped portion thereof through the looped portion thereof.

A still further object of the invention is to simplify the mechanism for causing the gripped portion of the filament to be pulled through the looped portion thereof. More specifically, the filament or thread to be knotted is wrapped around the two jaws to form a loop and after the filament or thread has been gripped by the jaws at a point removed from said loop, the loop is pushed off of the jaws while the latter still retain their grip on the filament so that the gripped portion of the filament is caused to be passed through the loop during the removal of the latter from the jaws.

With these and other objects in view, the invention consists in certain details of construction and combinations and arrangements of parts, all as will hereinafter be more fully described and the novel features thereof particularly pointed out in the appended claims.

In the accompanying drawings—

Figure 1 shows the present knotter mechanism adapted to what is termed a thread marker machine, this view being a side elevation with the base and a portion of the operating lever shown in section;

Fig. 2 is a detail sectional view on the line 2—2 of Fig. 1;

Fig. 3 is a vertical sectional view taken longitudinally of the needle support;

Fig. 4 is a top plan view of the machine base, on a smaller scale, with the top wall of the base broken away for the purpose of illustrating what will be termed the normal positions of the several instrumentalities of the knotter and its actuating mechanism;

Fig. 5 is an enlarged top plan view of the base with the upper wall broken away illustrating what will be termed the first position occupied by the knotting mechanism in the forming of a knot;

2

Fig. 6 is a vertical sectional view on the line 6—6 of Fig. 5;

Fig. 7 is a horizontal sectional view on the line 7—7 of Fig. 6;

Fig. 8 is a view similar to Fig. 5 showing what is termed the second position occupied by the knotter mechanism;

Fig. 9 is a view similar to Fig. 8 showing the thread or filament in position for the knot to be formed therein;

Fig. 10 is a detail sectional view on the line 10—10 of Fig. 9;

Fig. 11 is a detail top plan view of the knotter illustrating an intermediate portion of the same 15 in the formation of the knot;

Fig. 12 is a detail sectional view on the line 12—12 of Fig. 11;

Fig. 13 is a top plan view of the knotter illustrating the same in the position occupied by the latter immediately before the completed knot is removed from the knotter jaws;

Fig. 14 is a similar view illustrating the knot immediately after it is freed from the jaws of the knotter;

Fig. 15 is a vertical sectional view on the line 15—15 of Fig. 5;

Fig. 16 is a sectional view on the line 16—16 of Fig. 15;

Fig. 17 is a view similar to Fig. 1 illustrating, more or less diagrammatically, the use of the present knotter in what will be called a package tying machine;

Fig. 18 is a detail plan view of the end portion of the package tying machine base; and

Fig. 19 is a perspective view of a modified form of ejector plate.

It is to be understood that the present knotter may be utilized in forming knots in threads, cords or strands, although the terms "binding filament" and "thread" are adopted in the following description merely for purposes of convenience and are used interchangeably to designate any type of threads or strands or the like. The present knotter is also susceptible of various uses in that 40 it can be adapted to various types of machines and, for this reason, it has been shown in conjunction with what is known as a thread marker machine in Figs. 1 to 16 and in association with a package tying machine in Fig. 17.

In so-called thread marker machines such as 45 illustrated in Fig. 1 the thread 26 is adapted to be passed through a number of plies of fabric on the supporting surface 20 of the machine base and the thread knotted at a point below the surface 50 20 or below the lowermost ply of fabric in order

to prevent accidental withdrawal of the thread when the plies of fabric are removed from support 20. For a clearer understanding of the purposes of such a machine it may be said that in the production of clothing, for instance men's and ladies' suits, by the larger tailoring establishments a plurality of plies of fabric are stacked and cut in one operation and, for instance, say in the case of men's coats, it is the practice to mark the several plies while still stacked one upon another with lengths of thread extending through them at various points to denote where buttons are to be attached or to denote the corners of pockets and other points at which subsequent work is to be performed on the several pieces after they have been separated. In separating the several plies the thread is cut between each two thicknesses of material so that each piece of fabric carries a short length of thread at each of the points mentioned and, as previously indicated, it is desirable to tie a knot in the thread before the pieces of fabric are separated in order to prevent accidental withdrawal of the thread from one or more of the stacked plies of fabric.

The surface 20 on which the plies of fabric are supported constitutes the upper wall of a hollow base and the lower or bottom wall of said base is indicated at 21. Mounted on the upper wall 20 of the base is a bracket arm 22 which projects over the base and has slidably mounted in its upper extremity a plunger 23 depressible by an operating lever 24 to advance needle 25 and thread 26 downwardly and through a needle opening 27 in surface 20. Plunger 23 also has associated therewith a presser foot 28 which engages and holds the goods firmly on the base while the goods are penetrated by the needle. As shown in Fig. 3, the plunger 23 is of tubular formation and slides on a tube 29 rigidly mounted in the bracket arm 22 by a set screw 30, being guided in this sliding movement by a pin 31 carried by said plunger engaging in a slot 32 in tube 29.

Needle 25 is carried on a rod-like needle arm 33 and the latter has its upper end removably secured in a cap 34 threaded in the upper end of plunger 23. Presser foot 28 is carried on the lower end of a tubular member 35 slidably received in the lower end of tube 29. At the upper end of this tube 35 which carries the presser foot there is a collar 36 and attached to said collar is a lug 37 adapted to travel in slot 32 for the purpose of guiding the movement of the presser foot. A coil spring 38 is interposed between collar 36 and the lower end of tube 29 and the second coil spring 39 is interposed between said collar 36 and the plug or cap 34 with the result that when the plunger 23 is depressed by downward movement of the operating lever, spring 38 is compressed between collar 36 and the bottom of the tube and spring 39 is compressed between cap 34 and collar 36. Thus the two springs become loaded and, when the operating lever 24 is released in its lowermost position, they function to retract the needle from the goods and to return the presser foot and plunger tube 23 to their normal raised positions.

The vertical reciprocatory motion of the plunger tube 23 is compensated for by the operating lever being pivotally attached to the tube, as indicated at 40, and the lever itself is formed with telescoping sections 41, 42, the latter being mounted on a pivot pin 43 journaled in an extension 44 of the bracket arm 22. Referring to Figs. 1 and 2, a gear segment 45 is also mounted

on pivot pin 43 and the teeth 46 of said segment engage a gear 47 mounted on a stub shaft 48 journaled in the bracket arm. Shaft 48 carries a second gear 49 which meshes with the teeth 50 of a rack bar 51 slidably secured on the bracket arm by bolts 52 which extend through slots 53 in the rack bar and are threaded in suitable sockets in the bracket arm. Rack bar 51 is provided with a downwardly offset depending end 51a which protrudes through an opening 54 in the upper base wall and attached to the lower end of said depending extension is a rack bar 55 (see also Fig. 4). The teeth 55a of rack bar 55 engage a gear 56 on a shaft 57 mounted in the lower base wall and fast with gear 56 is a larger gear 58 so that the gears 56, 58 rotate in unison on shaft 57. Rack bar 55 may be slidably secured in guides 59 on the lower base wall 21. Gear 58 meshes with the teeth 60a of another gear 60 also slidably held on lower base wall 21 by guide brackets 61. Thus, oscillation or rocking of the operating lever 24 imparts a reciprocatory motion to rack 60 for operating the knot forming mechanism which will now be described.

When the thread carrying needle 25 is fully depressed the eye portion thereof is received in a tubular guide 62 mounted on the lower base wall. The upper end of guide 62 is cut away, as at 63, so that the thread 26 may be engaged by a hooked shaped member and pulled into position to be engaged by the knitter jaws. This thread engaging member preferably consists of a hook member 64 pivotally carried on a pin 65 in the outer end of an arm 66 whose opposite end is formed with an enlarged hub portion journaled on a shaft 67 mounted in the base. Where this thread engaging element takes the form of a hook, as shown, the thread is doubled upon itself so that, in a sense, a loop is formed therein but the presence of such a loop is not actually necessary in the knotting of the thread and the loop so formed is not to be confused with the loop which is subsequently produced in the thread in actually forming the knot. The enlarged hub portion of arm 66 is formed or provided with a gear 68 which meshes with a gear 69 on a shaft 70 and said gear 69 is adapted to be actuated by the teeth of another rack 71 fastened on the upper surface of rack 60. For purposes which will later appear gear 69 is of the mutilated type in that for a portion of its periphery it is provided with an extension 69a formed with a flat surface adapted to engage against the straight edge portion 71a and rack 71 at certain times in the cycle of operation of the knitter in order to lock arm 66 against motion. Referring to Fig. 4, hook 64 and its arm 66 are shown in what is their normal position at which time rack 60 with rack 71 are at the right-hand limit of their movement (as viewed in Fig. 9) and at which time the operating lever will be in its raised position. Fast on the hub of arm 66 is what will be termed the thread shifter 72 which is also shown in its normal position in Fig. 4. Thus, both the thread engaging hook 64 and the thread shifter 72 are normally positioned to one side of the needle guide 62 but, when operating lever 24 is depressed, rack 55, gears 56, 58, and rack 60, together with rack 71, will be moved in the directions indicated by the arrows in Fig. 4, and when the teeth of rack 71 actuate gears 69, 68, the thread shifter 72 and the thread engaging hook 64 will be moved to the positions in which they are shown in Fig. 5. When the parts assume their normal positions, as shown in Fig. 4, a dog 73 pivotally mounted on a

pin 74 engages the thread engaging hook 64 and rocks the latter on its pivot pin against the tension of a spring 65a (for a purpose which will later appear) and when rack 71 is moved to the left, as viewed in Fig. 5, dog 73 is swung on its pivot pin under the influence of a spring 74a with the result that hook 64 is free to turn on its pivot pin on arm 66 while being moved to the position shown in Fig. 5. This movement of hook 64 to the position shown in Fig. 5 is for the purpose of permitting the hook to catch the thread 26 in the initial portion of the return movement of arm 66 and hook 64 to their normal positions. As the hook 64 approaches the position shown in Fig. 5 it engages a stop 75 which swings or "cocks" it against the pressure of spring 65 so that the instant arm 66 starts its return movement, the hook will have a slight independent motion of its own to engage and catch the thread.

When the operating lever is released and returns to its normal position hook 64 engages and retains the thread and as the said hook returns to its normal position it pulls a length of the thread past a pair of jaws which constitute part of the knotter for purposes which will presently appear. The return motion of the thread shifter 72 also causes the length of thread to be positioned at a point where it also can be engaged by said jaws to form a loop therein. The successive positions of the thread at these points in the cycle of operations are illustrated in Figs. 8 and 9. The knotting mechanism is of a type capable of tying a bow knot and comprises the two relatively movable jaws 76, 77, the jaw 77 being pivoted at 78 on the other jaw 76 and yieldingly held in closed position by spring 79 attached to jaw 76 which is mounted on a shaft 80 journaled in the base wall 21. Also mounted on base 21 is a cam 81 which is engaged by cam roller 82 carried on the shank portion of jaw 77, the contour of said cam being such that jaw 77 is rocked on its pivot as the two jaws, with shaft 80, are rocked by a gear 83 on said shaft engaging the teeth 84 on the adjacent end of rack 60. Normally, the knotter jaws occupy the positions in which they are shown in Fig. 4, but, when the operating lever is depressed, the jaws are revolved in a counter-clockwise direction to the position shown in Fig. 8, ready to start the knot forming operation. Gear 83 is of the mutilated type having a flat surface 85 adapted to engage straight edge portions of rack 60 at opposite ends of teeth 84 to hold the knotter jaws against rotation when they occupy the positions in which they are shown in Figs. 4 and 5. It will be observed that the relative vertical locations of hook 64, jaws 76, 77, and thread shifter 72, are such that the hook 64, which is positioned in a plane below the jaws, will draw the thread under the jaws while the shifter 72 is located in a plane above the jaws so as to cause the thread to be more or less vertically disposed between the jaws and said shifter. In other words, at the time hook 64 and thread shifter 72 have assumed the positions shown in Fig. 5, they are both positioned at the same side, so to speak, of the jaws 76, 77, so that, when these thread engaging members shift to the positions in which they are shown in Fig. 9, at which time the hook 64 and shifter 72 are positioned at opposite sides of the jaws, the thread will extend from hook 64 under the jaws and then upwardly to the point at which it is engaged by the shifter 72, this upwardly extending portion of the thread being so positioned as to be engaged by the jaws when

the latter are revolved, as illustrated in Figs. 10 and 11.

Assuming the operating lever has been depressed to its lowermost limit of travel so that the thread has been carried through the plies of fabric and the elements described are in the positions illustrated in Fig. 5, and that the lever is then released, the cycle of operations in forming the knot during the return movement of operating lever 23 is as follows: During the initial portion of the return movement of rack bar 60, the teeth of rack 71 actuate gears 69, 68, to move the thread engaging hook 64 and the thread shifter 72 to successive positions illustrated in Figs. 8 and 9. At this time, as shown in Fig. 9, rack teeth 84 have engaged gear 83 and started the reverse or clockwise rotation of the knotter jaws 76, 77, and as the jaws continue to so revolve they engage the thread at a point between themselves and the thread shifter 72 so that the thread is wrapped or looped around them, as shown in Figs. 10 and 12, and the jaws are then opened by cam roller 83 passing over the higher portion of cam 81 to receive the thread. This is accomplished by jaw 77 being depressed to a point below that portion of the thread between hook 64 and the loop of thread formed around the jaws before the revolving jaws reach the limit of their return movement to normal position. Immediately before the jaws reach their normal position, they are closed by cam roller 82 engaging a lower portion of its associated cam surface. The parts are then in the positions shown in Fig. 13 with a portion of the thread formed in a loop around the jaws and the thread between the said loop and the hook 64 gripped in the jaws under the tension of spring 79. At this point it will be observed that rack teeth 84 have become disengaged from gear 83 but that the rack 60 has not yet fully returned to its normal position.

It is during this final portion of the return movement of rack 60 that the last step in the formation of the knot and the freeing of the knotted thread from the jaws is effected. This is accomplished as follows: A plate 100, which will be called the ejector plate, has an extension 101 on which is pivoted, at 102, a pawl 103 yieldingly held by a spring 104 against a stop pin 105 on said extension and said pawl normally engages in a detent 106 in rack bar 60 so that the ejector plate is normally held in what might be termed its normal advanced position shown in Fig. 4. However, during depression of the operating lever, the rack bar 60 moves, as indicated by the arrow in Fig. 4, and the ejector plate is retracted by a spring 107 attached to base wall 21 and the ejector plate extension 101, under which conditions the pawl 103 is disengaged from detent 106. This retractive movement of the extension and ejector plate is limited by a stop pin 108 so that the plate assumes the position in which it is shown in Figs. 5, 8 and 9. With the plate located in this retracted position, the thread is then moved into position with respect to an edge 109 of said plate by the previously described return swinging motion of the thread shifter 72, as shown in Figs. 9, 13 and 14. In machines of the present type, that is thread marker machines, this edge portion, indicated at 109, may be formed by a slot 110 in the ejector plate (see Fig. 14), said slot being formed with an angularly disposed extension 111 adapted to register with the needle guide 62, so that the needle, with the thread, can pass through the plate when it is forced through the fabric. During the final por-

tion of the return movement of rack bar 60, pawl 103 reenters detent 106 and as the swinging movement of pawl 103 is limited by pin 105 against which it is yieldingly held by spring 104, the extension 101 and ejector plate 100 are returned to their original normal positions with the result that the ejector plate engages the thread and pulls the loop of thread wrapped around the jaws off of the latter. Thus, the portion of the thread which, at that time, is held between the jaws is pulled through the loop that had previously been wrapped around the jaws. Finally, the ejector plate 100 pulls the thread from between the jaws, the strength of spring 79 being such as to permit this. At the same time, the dog 73 is engaged by the end of rack bar 71 and rocked from the position shown in Fig. 8, which it assumed when said rack bar was retracted by depression of the operating handle, to its normal position shown in Figs. 4 and 14, with the result that hook 64 is rocked on its pivot to disengage the thread therefrom. Thus, the knotted thread is completely freed (see Fig. 14) and the parts have assumed their normal positions, ready for the next cycle of operations.

Fig. 19 shows a modified form of ejector plate in the sense that said plate is not slotted as is the plate 100 illustrated in Figs. 13 and 14. In this modified form of plate indicated at 100^a, the thread can engage against the edge 100^b when the needle penetrates the goods and said thread is shifted to a position against the front edge 100^c of said plate by the thread shifter to position the thread in the path of the ejector plate for the purpose of removing it from the knotted.

A further adaptation of the present knotted mechanism is disclosed in Figs. 17 and 18 wherein a package tying machine is illustrated more or less diagrammatically in view of the fact that the knotted mechanism itself is of the same construction as that previously illustrated and described in connection with the thread marker machine of Figs. 1 to 16. In this so-called package tying machine, the package to be tied is supported on base wall 20 with the cord or other binding element wrapped around it. Preferably, the cord 26^a is supplied from a reel or bobbin 150 located above the base and the free end of the cord is adapted to be temporarily anchored, so to speak, below the base. A notched plate 151, in which the cord is frictionally gripped is shown for this purpose in the present instance. With this arrangement, after the operating lever is depressed, the bundle or package, indicated in dotted lines at 152, is slid on to the base surface 20, during which movement it will engage the cord and the latter will be wrapped around three sides of the package. The cord is then severed at a point above the package to provide an additional length of cord sufficient to be wrapped along the fourth side of the package with this severed end extending downwardly approximately to the plate 151. The original free end of the cord can then be freed from plate 151 and the knotted actuated as previously described. If desired, the operator can hold the two ends of the cord loosely in one hand when the depressed operating lever is released, so as to place a slight tension on the cord while the hook 64, shifter 72 and jaws 76, 77 are in motion.

The top and bottom plates 20, 21 of the base are recessed at their forward ends as at 153 and the inner ends of these recesses serve to position the cord ends where they will be engaged by hook 64 and shifter 72. Thus, these recessed portions

of the base serve the function of positioning the cords in the absence of the thread needle 25, which, together with the tubular needle guide 62, is eliminated in the tying machine. The tying machine also differs from the marking machine in that the bracket arm 22 is preferably offset rearwardly, instead of overhanging the surface 20 in order to provide clearance for large packages. Furthermore, the plunger tube 23 of the marking machine is, of course, dispensed with in the tying machine and, for this reason, the operating lever for the tying machine, indicated at 42^a, need not be made of telescoping sections. With these exceptions the two machines may be of like construction and operation.

What is claimed is:

1. In a knot tying machine, a pair of rotatable, pivotally associated jaws, a shaft, an arm on said shaft, a thread engaging member on said 20 arm located below said jaws, means for rocking said shaft to move said member in one direction to engage a thread at one side of said jaws and to move said member in the opposite direction to draw the thread past and beneath the jaws to 25 the opposite side of the latter, a second thread engaging member located above and at the first mentioned side of the jaws, means for revolving the jaws to engage the thread at a point intermediate the jaws and upper thread engaging 30 member to loop the thread around the jaws, means for opening and closing said jaws to grip the thread at a point intermediate the loop and the lower thread engaging member, and a plate movable longitudinally of the jaws and engageable with said thread to remove said loop from around the jaws, and means for maintaining said jaws closed during removal of the loop whereby the thread held between said jaws is drawn through the loop.
2. In a knot tying mechanism, a base, a pair of shafts journaled in said base, a pair of pivotally associated jaws on one shaft, a thread engaging member on the second shaft normally positioned at one side of said jaws in a plane 45 below the latter, means comprising a rack bar for revolving said second shaft in one direction to move said member to the opposite side of the jaws in position to engage a thread and for revolving said member in the opposite direction to draw a thread past and beneath the jaws, a second thread engaging member on said second shaft located at said opposite side of the jaws in a plane above the latter whereby a thread extending between said members will be disposed 50 from the lower member under said jaws and then upwardly to the upper member, a rack bar for revolving said jaws to engage the upwardly disposed portion of the thread and wrap the same in a loop around the jaws, means for opening 55 and closing the jaws to grip said thread at a point intermediate said loop and the lower thread engaging member, and means operable by one of said rack bars for disengaging said loop from around the jaws while the thread is gripped between the jaws.
3. In a knot tying mechanism, a base, a pair of shafts journaled in said base, a pair of pivotally associated jaws on one shaft, a thread engaging member on the second shaft normally positioned at one side of said jaws in a plane below 70 the latter, means comprising a rack bar for revolving said second shaft in one direction to move said member to the opposite side of the jaws in position to engage a thread and for revolving said member in the opposite direction to draw

a thread past and beneath the jaws, a second thread engaging member on said second shaft located at said opposite side of the jaws in a plane above the latter whereby a thread extending between said members will be disposed from the lower member under said jaws and then upwardly to the upper member, a rack bar for revolving said jaws to engage the upwardly disposed portion of the thread and wrap the same in a loop around the jaws, means for opening and closing the jaws to grip said thread at a point intermediate said loop and the lower thread engaging member, a slide movable on said base by one of said rack bars, and a plate on said slide engageable with said thread for disengaging said loop from around said jaws while the thread is gripped between the jaws.
